E. T. Silvius,
ATTORNEY.

UNITED STATES PATENT OFFICE.

JAMES A. NICKERSON, OF INDIANAPOLIS, INDIANA.

AUTOMATIC WALL-PAPER EXHIBITOR OR ADVERTISER.

Application filed June 3, 1923. Serial No. 644,438.

This invention relates to a machine for holding samples of wall paper, or sheets containing advertisements and automatically shifting them to bring them successively to view, the invention having references more particularly to hingedly supported wings or frames for holding the samples or sheets, and to mechanism for automatically shifting or turning the wings or frames so that the two sides thereof may be alternately viewed.

An object of the invention is to provide an automatic exhibitor which shall be so constructed as to compactly hold a large number of sheets of paper or other substances, to be exhibited to prospective customers or others without the necessity of constant attendance of a salesman or demonstrator.

Another object is to provide simple and compact mechanism whereby to move hingedly supported wings first in one direction successively and subsequently in the opposite direction, to alternately bring both sides of the wings into view and thus afford the maximum advertising space.

A further object is to provide improved mechanism for periodically swinging hingedly supported wings on which paper or other sheets may be displayed, which mechanism may be so constructed as to permit removal of any of the wings and the application of other wings having different samples or sheets to be exhibited.

A still further object is to provide an exhibitor of the above-mentioned character which shall be so constructed as to be adapted to be placed in salesrooms or store windows and as a portable electrically operated apparatus that may be readily moved from place to place, and which shall be adapted to be inexpensively constructed and be durable and economical in use.

With the above-mentioned and other objects in view, the invention consists in an automatically acting exhibiting machine having improved display wings and also novel operating and controlling mechanism, operating to shift samples or advertising sheets intermittently and permit each one to be seen a sufficiently long time to be inspected or read; and the invention consists also further in the parts and combinations and arrangements of parts as hereinafter particularly described and further defined in the claims appended hereto.

Referring to the drawings, Figure 1 is a perspective view of the exhibitor as preferably constructed, all but two of the wings thereof being omitted in the interest of 60 clearness; Fig. 2 is a fragmentary top plan of the improved machine; Fig. 3 is a fragmentary detail on an enlarged scale, showing a number of associated parts, looking upward to clearly see the mode of operation 65 of the wings; Fig. 4 is a fragmentary perspective view on an enlarged scale, showing details of the wing structure; Fig. 5 is a fragmentary transverse vertical section of the machine, showing particularly the hing- 70 ing connections of the improved wing; Fig. 6 is a fragmentary side view of the machine showing operating apparatus thereof; Fig. 7 is a fragmentary section showing details on an enlarged scale comprised in the wing- 75 operating mechanism; Fig. 8 is a longitudinal sectional view, partially broken away, showing a compound transmission shaft for reversing the motion of the machine; Fig. 9 is a fragmentary rear elevation of the machine on an enlarged scale; Fig. 10 is a vertical section transversely of the machine on an enlarged scale illustrating associated elements of controlling apparatus appearing in elevation in the preceding Figure; and, Fig. 11 is a fragmentary view on the line XI—XI in Fig. 10.

Similar reference characters in the different figures of the drawings indicate corresponding elements or features of construction herein referred to in detail.

The invention as preferably constructed comprises two foot or base members 1 and 2 which vertically support two posts 3 and 4 to which a lower rail 5 is connected adjacent to the foot members. A frame beam 6 is secured to the upper portions of the posts. The lower rail has a ledge 7 fixed on its forward side to bodily support the wings and it has pivot holes 8 therein to receive hinge-pins or pivots. An upper rail 9 is secured to the upper portions of the posts and it has a face plate 10 on its forward edge, the rail preferably being composed of two thicknesses of metal.

A suitable number of wings or leaves are provided which preferably are composed of light-weight material such as a fiber board or other veneering body part 11 and a metallic edge binding 12. The lower rear corner of each wing has a hinge ear 13 thereon provided with a hinge-pin 14 that extends

into one of the pin holes 8. The upper rearward corner of each wing is provided with a novel hinge ear and hollow operating lever combined which comprises two side plates 15 and 16 fixed to and projecting beyond the binding 12, and a top plate 17 integral with the side plates and arranged under the upper bar 9, the top plate 17 having a hinge-pin 18 fixed thereto that is connected with the rail 9, the arrangement being such that the wing when extended straight forward is slightly tilted with its end slightly higher than the plane of the ledge 7, to insure gravity movement of the wing after having been swung from extended or mid-position. In some cases each wing has side guide frame bars 19 and 20 and a bottom stop bar 21 to receive and hold an advertising card on the face of the wing and permit the card to be readily withdrawn to be replaced by another, especially for advertising purposes, to obviate the necessity of pasting or otherwise securing the advertising sheet to the wing.

25 A guide-bar 22 and a screw 23 are mounted in parallel arrangement in the upper portions of the posts 3 and 4, the bar being stationary and the screw suitably journaled in and extending through the posts. A traveler head 24 is slidably guided on the guide bar and is threaded as a nut on the screw. The head has a horizontal guide bore 25 therein in the rear end of which a plug 26 is secured which resists a spring 27 arranged 30 in the bore and engaging the inner end of a finger bar 28 to normally project it from the bore to engage the lever portions of the wings, and is yieldingly held by the spring in projected position permitting retraction 35 of the bar when not properly engaging a wing lever. The screw 23 has a pulley 29 fixed on one of its journals to rotate the screw in one direction, and a pulley 30 fixed on the remaining journal to rotate the screw 40 in the reverse direction.

45 A solid shaft 31 is arranged rotatably in two hollow clutch shafts 32 and 33 that are rotatably mounted on the rearward sides of the posts 3 and 4, so as to not have endwise movement. The shaft 32 has a pulley 34 fixed thereto, and a belt 35 is connected with the pulley and also with the pulley 29. A pulley 36 is fixed to the shaft 33 and a belt 37 is connected therewith and also in crossed arrangement with the pulley 30. The shaft 31 extends out beyond the pulley 36 and has a pulley 38 secured thereto. A bracket 39 is secured to the post 4 and supports an electric motor 40 that has a driving shaft 41 to which a pulley 42 is secured, and a belt 43 is connected with the pulley and also with the pulley 38, whereby the shaft 31 is constantly rotated in one direction. A clutch sleeve 44 is slidably arranged on the shaft 31 and is shorter than the distance between

the shafts 32 and 33, the sleeve having a longitudinal slot 45 therein into which a driving pin 46 extends that is secured to the shaft 31, enabling the latter to constantly rotate the sleeve. The inner end of the hollow shaft 32 has a clutch tooth 47 thereon which may be engaged by a clutch tooth 48 with which the adjacent end of the sleeve 44 is provided; the shaft 33 is provided with a clutch tooth 49 which may be engaged by a clutch tooth 50 with which the adjacent end of the sleeve 44 is provided, and the sleeve has a disk-shaped collar 51 fixed on the middle portion thereof whereby to shift the sleeve so as to clutch the shaft 31 alternately with the shafts 32 and 33 to rotate the hollow shafts, the shaft 32 causing the screw 23 to be rotated in one direction and the shaft 33 by means of the crossed belt 37 causing the screw to be rotated in the opposite direction.

50 For causing the clutch sleeve 44 to be operated and reliably a shifting lever base 52 is secured to the back of the frame member 6 and it is provided with a centrally arranged pivot rod 53 to which a shifting lever 54 is connected between its ends, the lever extending upward and having connecting rods 55 and 56 pivoted thereto to extend away in opposite directions and they are pivotally connected to collars 57 and 58 respectively, which are mounted to slide on the guide bar 22 so as to be alternately engaged by the traveler head 24. The shifting lever extends downward beyond its pivot and has a finger 59 to engage one side and another finger 60 to engage the opposite side of the collar 51 as the lever is moved automatically in operation. The base 52 has bearing rollers 61 and 62 mounted therein above and below the pivot rod respectively, and the back of the lever 54 has wedge-shaped portions 63 and 64 to engage the rollers, being forced into contact therewith by a coil spring 65 bearing at one end against the lever and extending about the pivot rod on which a nut 66 is secured to adjust the tension of the spring, the arrangement being such that as the lever 54 is being moved slightly beyond its mid-position the wedge portions against the rollers cause sudden forward movement of the lever to the extent of its travel. Preferably the spring and associated parts are covered by a cap 67 that is screwed onto the end of the pivot rod 53. The base 52 has two abutments 68 and 69 thereon arranged at suitable distances from the lever 54 and they support adjusting screws 70 and 71 respectively, against which the lever is stopped after each rocking movement.

55 For the purpose of informing observers as to which of the wings is to be moved in operation a suitable pointer is provided which may comprise a base plate 72 secured

upon the traveler head 24 and having a stem 73 thereon which supports a suitable body portion 74 which may represent a bust figure of a man having a head 75 and an arm 76, the 5 latter extending downwardly and forwardly of the face plate 10 and having a hand 77 thereon provided with an extended finger 78 pointing downward, the position of the finger being such as to always be approximately 10 above the wing next to be turned.

In practical use samples of wall paper or sheets having decorations thereon, or paintings or printed sheets are placed on the faces of the wings where they may be advantageously observed. Electric current may be variously supplied to the motor which in operation drives the belt 43, the pulley 28 and the shaft 31 which in turn rotates the sleeve 44. When the sleeve is clutched to 20 the hollow shaft 32 the shaft 31 rotates in the shaft 33, and the screw 23 is rotated in one direction by the belt 35 on the pulleys 29 and 34, as represented in Fig. 9, the shaft 33 being idly rotated in the opposite direction 25 by means of the crossed belt 37 being driven by the screw. The traveler head in its movement comes into contact with the collar 57 and pushes it along the guide bar 22 until the shifting lever 54 is drawn past 30 its midposition, the lever being suddenly thrust forward as above-explained until stopped, and during its movement the finger 60 is brought into engagement with the collar 51 and forces the sleeve 44 over for 35 clutching engagement with the shaft 33 as indicated by dotted lines in Fig. 9, so that reversing occurs by driving the shaft 33 and causing the pulley 36 to drive the crossed belt 37 whereby the screw is rotated 40 in reverse direction, leaving the shaft 32 to be idly rotated by the screw and the belt 35. As the finger bar 28 is carried along by the traveler head 24 towards the ends of the plates 15 and 16 on the wings, the plates 45 being extended angularly towards the approaching finger bar, the latter engages the plate that is the nearer to the screw and swings the wing on its hinges until the wing is carried around to the opposite angle with 50 the finger bar between the two plates until the bar is carried away from and beyond the plate with which it had contact, the action being readily understood by reference to Fig. 3. In case the leaves are carelessly 55 placed in the machine without reference to the position of the traveler head, as the finger bar is carried against the outer side of one of the plates 15 or 16 improperly set for operation, the finger bar will slide along 60 the plate and be forced backward without damage to the parts until carried past the obstruction. When the leaves have been turned over in one direction and reversal of 65 the screw 23 occurs the leaves are again turned in succession in the opposite direc-

tion, so that one face of each of two leaves may always be viewed, or the attention of the observer may be concentrated on one face alone of each leaf as it is brought to view.

What I claim as new is:—

1. An automatic exhibitor including wings having ears hingedly supporting the wings, each wing having a projecting hollow operating lever, a reversible rotary screw 75 adjacent to all the leaves, and a guided traveler head operating on the screw and having a projecting finger bar to successively enter and operate the operating levers.

2. An automatic exhibitor including a 80 rotatably supported screw, wings having each an ear hingedly supported adjacent to the screw and having also an operating lever provided with two opposite plates at the ear, a guided traveler head engaged and 85 operated by the screw and having a finger bar to engage and operate one of the plates of the operating levers, and mechanism controlled by the traveler head to rotate and reverse the motion of the screw. 90

3. An automatic exhibitor including hingedly supported wings having each an operating lever, each lever having a hollow end, a rotatable reversible screw having two drive wheels fixed thereto, a guide bar 95 stationarily supported adjacent to the screw, a traveler head operated by the screw and guided on the guide bar provided with a finger to successively enter the hollow ends to operate the operating levers, and mechanism to rotate the drive wheels alternately in 100 opposite directions.

4. An automatic exhibitor including wings having ears hingedly supporting the wings, each wing having a projecting hollow 105 operating lever, a reversible rotary screw adjacent to all the levers, a guide bar fixedly supported adjacent to the screw, and a traveler head slidingly guided on the guide bar and operated by the screw, the traveler 110 head being provided with a spring pressed finger bar to successively enter and operate the hollow levers.

5. An automatic exhibitor including hingedly supported wings, a slidably guided 115 traveler head, means to enable the head to successively swing the wings, a rotatably supported screw engaging and operating the traveler head, means to rotate the screw alternately in opposite directions, and a figure carried upon the traveler head and having a pointer thereon directed towards the wings successively in advance of their swinging movements. 120

6. An automatic exhibitor including wings 125 having hingedly supported ears, one ear on each wing being provided with an operating lever composed of two plates projecting from the ear, a reversible rotary screw adjacent to the levers, and a guided traveler head 130

operating on the screw and provided with a finger bar to be carried successively into the spaces between the plates of the operating levers and into contact with the plate ahead 5 of the bar.

7. An automatic exhibitor including a plurality of vertical hingedly supported wings, each wing having a hollow operating lever at the top thereof, a reversible horizontally arranged screw rotatably supported adjacent to the operating levers, a traveler head engaged and operated by the screw and provided with a projecting yielding finger bar to successively enter and 10 move the hollow operating levers, and a supported guide bar engaged by the traveler head to prevent rotation of the head with the screw.

8. An automatic exhibitor including wings 20 having hingedly supported ears, one ear on each wing being provided with an operating lever having two engagement members extending from the ear, a reversible rotary screw adjacent to the levers, and a guided traveler head operated by the screw and provided with a projecting retractile finger bar to be carried into engagement successively with one of the members of the operating levers to operate the levers when operable or to 25 be retracted by the other of the members of the levers when not in operable position.

9. An automatic exhibitor including a rotatably supported screw having two pulleys fixed thereto, wings having each an ear 30 hingedly supported adjacent to the screw and having also an operating lever at the ear, a guided traveler head engaged and operated by the screw, the head being provided with a projecting finger bar to successively engage and operate the levers, a transmission shaft rotatably supported and provided with two driving pulleys belted reversely to the pulleys respectively on the screw, and clutch mechanism controlled by 35 the traveler head to clutch the driving pulleys alternately to the transmission shaft.

10. An automatic exhibitor including a plurality of vertical hingedly supported wings, a horizontal rotatable screw, a guided traveler head connected with and operated by the screw, means operated by the traveler head to successively swing the wings, a horizontal rotatable transmission shaft, two hollow shafts rotatable on the transmission shaft, means to enable one of the hollow shafts to rotate the screw in one direction, means to enable the other of the hollow shafts to rotate the screw in the reverse direction, and means controlled by 40 the traveler head to alternately clutch the hollow shafts to the transmission shaft.

11. An automatic exhibitor including a plurality of vertical hingedly supported wings, each wing being provided with two 45 operating lever members, a screw horizon-

tally arranged rotatably in proximity to the upper portions of the wings and having two driven pulleys fixed thereto, a guide bar supported adjacent to the screw, a traveler head connected with the screw to be operated thereby and having contact with the guide bar, a finger carried by the traveler head to successively operate between the lever members to swing the wings, and mechanism for 50 rotating and reversing the screw comprising two alternately rotated driving pulleys, an open belt connected with one of the driving pulleys and one of the driven pulleys, and a crossed belt connected with the remaining one of the driving pulleys and the 55 remaining one of the driven pulleys.

12. An automatic exhibitor comprising an upright frame having a bracket on its rear portion and hinge-supporting rails on its front portion, each rail being horizontal and having a plurality of pin-holes therein, a plurality of wings provided with hinge pins arranged in the pin-holes of said rails, the wings being uprightly arranged opposite to the front of the frame, a screw horizontally journaled on the upper portion of the frame, two driven pulleys secured to the screw beyond the opposite sides respectively of the frame, a guide bar horizontally arranged adjacent to the screw and secured to the frame, a traveler head threaded on the screw to be moved thereby and having contact for guidance on the guide bar, means operated by the traveler head to successively swing the wings, a transmission shaft having two hollow shafts spaced apart and rotatable thereon, the hollow shafts being rotatably supported on the rear portion of the frame and having each a driving pulley thereon, two belts connected with the driving pulleys respectively and with the driven pulleys respectively, one of the belts being in open and the other crossed arrangement, a clutch sleeve splined on the transmission shaft between the hollow shafts and having a collar fixed thereon, the two ends of the sleeve being adapted to be clutched alternately to the hollow shafts, a shifter lever pivoted on the rear portion of the frame and having two fingers to contact alternately with opposite sides respectively of the collar on said sleeve, two slide collars guided on said horizontal guide bar to be alternately moved by the traveler head, two link rods pivoted to the slide collars respectively and to the shifter lever, a transmission pulley secured to the transmission shaft, and a motor mounted on said bracket and having a driving pulley belted to said transmission pulley.

13. In an automatic exhibitor, the combination of hingedly supported wings, a horizontal guide bar, a horizontal transmission shaft and connecting means to transmit motion alternately in opposite directions, said 125

means including a movable clutch sleeve having a disk fixed thereto, a rotatable screw operated by said means, two slide collars movable separately on said guide rod, a traveler head operated by said screw between said collars to swing said wings, a pivoted shifter lever linked to said collars and having fingers to alternately engage said disk, and means to automatically complete movement of the shifter lever following starting movement by action of either of the slide collars.

14. In an automatic exhibitor, the combination with an upright frame, and a plurality of vertical wings hingedly connected to the front of the frame, of a horizontal screw rotatably supported on the upper portion of the frame, a traveler head threaded on the screw and movable thereby, means operated by the traveler head to successively swing the wings, transmission gearing on the back of the frame operatively connected with the screw to rotate the screw alternately in opposite directions, the gearing including a movable clutch sleeve having a disk fixed thereon, a horizontal guide bar secured to the frame adjacent to the screw and guiding the traveler head, two slide collars movable on the guide bar on opposite sides respectively of the traveler head, a base secured to the back of the frame, a pivot rod secured to the base, a shifter lever connected to the pivot rod and having two fingers adjacent to opposite sides respectively of said disk, the back of the lever having two wedge portions above and below the pivot rod, two bearing rollers mounted in said base above and below the pivot rod, a coil spring on said pivot rod bearing on the shifter lever, a nut on the pivot rod bearing on the spring, and two link rods pivoted to the slide collars respectively and to the shifter lever.

15. An automatic exhibitor including a rotatably supported screw, wings, each having an ear hingedly supported adjacent to the screw, each of said ears having two opposite plates, a guided traveler head engaged and operated back and forth by said screw and having a finger bar to engage and operate one of said plates to turn the wings.

In testimony whereof, I affix my signature on the 29th day of May, 1923.

JAMES A. NICKERSON.
